UNITED STATES PATENT OFFICE.

THOMAS B. DE FOREST, OF BIRMINGHAM, CONNECTICUT.

MACHINE FOR MAKING FOLDED TAGS.

Specification forming part of Letters Patent No. 44,496, dated September 27, 1864.

To all whom it may concern:

Be it known that I, T. B. DEFOREST, of Birmingham, of the county of New Haven, in the State of Connecticut, have invented a new and useful Machine for Making Folded Tags or Price Labels; and I do hereby declare that the following is a full and exact description thereof, reference being had to the accompanying drawings, making part of this application.

My invention has for its object to produce, by an automatic machine, what are known as "folded tags" or "price-labels," which consist of an oblong piece or short strip of paper or other suitable material, having one end folded over in a peculiar manner, and an eyelet inserted therein, through which to pass a string for the attachment of the tag or label to goods, &c.; and it consists, first, in an organized machine for making folded tags, in which the material from which the tags are formed is supplied by an intermittent feed-motion to a suitable table or sustaining surface, where it has performed upon it successively the several operations requisite to the production of a complete folded tag; secondly, in certain new combinations of mechanical devices for performing the several operations necessary to make a complete folded tag.

To enable those skilled in the art to make and use my invention, I will proceed to describe the construction and operation of my new tag-machine, referring by letters to the accompanying drawings, forming part of this application, and in which—

Figure is a top view of my improved machine for making tags. Fig. 2 is a side elevation of the same, looking in the direction indicated by the red arrow, Fig. 1, (and showing only one of the four carriages and folding and carrying mechanisms.) Fig. 3 is a partial similar view looking in the direction indicated by black arrow, Fig. 1. Fig. 4 is a vertical section at the line $x-x$, Fig. 1. Fig. 5 is a horizontal section at the line $y-y$, Fig. 2. Figs. 6, 7, 8 are detail views to be hereinafter more particularly explained.

In the several views or figures the same part will be found indicated by the same letter of reference.

The base of the machine consists of a suitable casting, A, of the form shown (or any other desired,) from which extend vertically

upward a shaft, B, and two plates, C and D. On the vertical shaft B is hung, a short distance above the base of the machine, a horizontal face-plate or circular disk, E, which turns freely on said shaft, and which may have arranged fast on its under side a suitable pulley, through the medium of which motion is imparted to the several parts of the machine. Immediately above the face-plate E (or its hub, rather) is arranged a hub, G, which turns freely on the shaft B as its axis, and from which extend, radially and equidistant, four horizontal arms, H H H H, each one of which carries a mechanism which will be presently explained. I I I I are four shorter arms or lugs which also project from the hub G, the object and functions of which will be presently explained.

The construction and operation of the machine may be more readily comprehended if it will be remembered that each one of the four mechanisms which I have just said is carried on each of the arms H, &c., carries a supply of material and performs the feeding, folding, and cutting off and discharging operations, each one coming at the proper time in the proper position to admit of the tag being punched and eyeleted by the mechanisms for performing these operations, which mechanisms are arranged, respectively, on the plates C and D.

The mechanism for punching the eye in the tag will be most clearly seen at Fig. 3, where a is the punch and b the lower hollow (punch or) die, each of which is arranged to work vertically in suitable bearings, and both of which are so actuated as to move toward and from each other in the same line of motion, the upper one penetrating the lower one. The punch a is actuated by a lever, J, pivoted at c , and driven by the pin d working in its slots f , while the hollow punch or die b is actuated upward by the cam K, and downward by a spiral spring arranged around its shank. The cam K is moved on its center g by means of a pin, h , working in its slot i , and said pin h and also the pin d (provided with suitable friction-collars) are projected from the side of a reciprocating vertical bar, L, which is arranged in suitable bearings on the plate C, and which is driven by the vibratory bar or arm M. This bar M is hung on a pivot, j , near

its center, and has that end which extends under the disk E provided with an anti-friction-wheel, k, against which the cam N operates at certain times, as will be presently explained.

The punching mechanism need not be more elaborately described, as it embraces no peculiarities which I deem new, in this application, and is very similar to that shown and described in the patent granted on the 13th day of January, 1863, to Linton DeForest.

The eyeletting, or eyelet-inserting mechanism which is arranged on plate D, (see Fig. 2,) consists of a horizontal bar, l, (to which eyelets are supplied from a hopper through a chute, O,) a feeder for carrying along an eyelet in the hollow bar l, a hollow lower die, m, and a centering-punch, n, and upper die, o, all arranged and operated in such manner as to automatically insert and clinch an eyelet in the tag, which is brought into the proper position to have the eyelet inserted in a manner to be presently described.

The punch n and die o are actuated by the lever P, and the die m by a cam, Q, said lever P and cam Q being driven, as shown, from the reciprocating bar R, which is operated by the arm S. This arm is made similar to that seen at M, and is operated upon in like manner by the same cam N. The feeder-bar, which feeds the eyelets (one at a time) to the inserting-dies, is pulled backward by a strap, g, passing over a fixed pulley, T, and attached to a vibrating angle-lever, U, (which is moved by a portion of the surface of cam Q,) and forward by a spring, r, made of rubber band, or of metal, in the usual manner.

I have not shown the hopper from which the eyelets are supplied, as it forms no part of my present invention; and I propose to use the apparatus shown and described in Letters Patent granted to me on the 13th day of January, 1863.

From each one of the arms H there extends up a curved stand, V, which supports the carriage and holding mechanism, and immediately below each of these curved stands V is arranged a reel, W, on which is a supply of paper or other material, from which the tags are to be made, in the form of a long strip, (wound up,) equal in width to the width of the tag to be made.

In Figures 1, 2, and 3, I have omitted (in each) three of the folding-mechanism carriages in order to make the drawings less complicated and more easily understood.

I will now describe the construction and operation of one of these mechanisms, which will answer for all of them, as the four are exact duplicates.

A² is the frame projecting up from stand V, and from which extends out a horizontal table or bed-plate, B². In the frame A² are hung in suitable boxes the feed-rolls C² D², the upper one of which is turned by a gear, B⁶, through the motion of the under one, which is rotated by a pinion, E², (on its shaft a²),

which meshes into a vertical rack, F². The upper feed-roll is hung in boxes capable of sliding vertically up and down, and said roll is held down with a spring-pressure onto the under roll by means of springs a⁵. (See Fig. 4.) The rack F is formed on a bar, the lower portion of which passes through a long bearing or box, G², formed on arms I H, and has its lower end kept down on the top surface of disk E by means of a rubber or other spring, c². The strip of paper wound on reel W has one end passed in between the rolls C² D², so that they will bite the paper, and the feeding will then be effected automatically by an intermittent rotation (in one direction) of the rolls C² and D², caused by the reciprocation of the rack F² up and down, although the said rack drives the pinion E² first in one direction and then in another. The intermittent motion just mentioned is imparted to the lower roll by reason of the pinion E² being arranged on shaft a² with a ratchet, so as to only affect the rotation of said shaft when turning in one direction.

G³ is a stand erected on the table B², in the upper portion of which slides in suitable ways, the carriage H², which carries the formers, over which the paper is folded, (as will be presently explained.) The carriage H² has a stand, I², on top, in which is pivoted the arm J², one end of which is provided with a roll or wheel, e², which works on the upper face of cam K², and the other end of which operates to depress at intervals the carriage L², in which are arranged the shanks f² g² of the formers h² i². The cam K² also operates (on its side surface) against the rear end of carriage H² to move it in one direction, said carriage being kept up against said cam by means of springs j².

M² is a carriage which is arranged to straddle the stand G², and which is reciprocated back and forth on each side of said stand by means of the cam N² and springs l². In this carriage, are formed two oblique slots, m² n², through which project pins n² n², from two carriages or sliding bars, o² o², which are arranged just beneath carriage M², and which are caused by the slots m² and pins n² to reciprocate at right angles to the motions of carriage M². The bars o² o² are provided with two arms, p² p², at the extremities of which are formed the folding-blades q² q².

On the extreme end of the table B² is arranged to slide in a suitable bearing, a bar, r², on one end of which is the folding-blade s², and the other end of which is acted upon by the rim N². (See Fig. 1.) This rim N², as will be seen, is concentric with the shaft B, (around which the folding mechanisms, &c., turn as a center,) and a little over a quarter of a circle in extent. Its office is to force in (toward the center of the machine and the shaft B) the bars r² at the proper time to produce a fold, and retain them in such position (against the tendency of the springs t²) for a given period.

P² is a cam, which is arranged just over the

disk E and held firmly by an arm or stand, Q², bolted to the base A. This cam P² lifts the racks F² at the proper times to effect the feeding of the paper. R² is the cutting-off knife, which cuts off the required length of paper fed onto the table B² to make a tag. This knife R² is forced down to cut by the outward motion of carriage H², which is provided on its under side with a lug, c⁵, which projects down and comes in contact with the inclined top surface of the stock S² of said knife. The said stock and knife are kept or held up by a spring, r². The four arms I are formed with four vertical boxes, T², in which work four vertical bars, U², carrying at their upper ends four wheels, V², which run on the top surface of a stationary collar, W², (on shaft B.) This collar has the top surface formed with a depression running about one-quarter around it, as seen at W², Fig. 6, which allows the wheels V², with their bars U², to drop down into a position in which they are operated upon by a lug, H³, projecting up from the top surface of the rotating disk E. On the plate D is arranged a stand, A³, in which is a spring-bolt, a³, (see Fig. 2,) that snaps or catches into a hole, b³, in the end of (each one of) the arms H, for the purpose of retaining the said arm H (and all the mechanism it carries) in a stationary condition. Said bolt is thrown back at the proper time to allow the arm H to move by a cam, B³, on the edge of disk E coming in contact with and pressing upon an arm, c³, (which moves the spring-bolt a³.)

A portion of the table B², on which the tag is formed, is made to slide back, (or toward the shaft B, to allow the completed tag to fall through and out of the machine. This portion of table B² has a projecting part, D³, (see Figs. 2 and 4,) which slides in ways E³ on the frame A², and which is kept out by a spring, d³, and forced in by the forward part of D³ coming in contact with the stationary finger or cam-bar, F³. (See Fig. 1.) At Figs. 7 and 8, I have shown a bottom and edge view of the disk E, and in these figures will be clearly seen the lug H³, which operates the bars U², and also the cams which operate the punching and eyeleting mechanisms and the retaining-bolt a³.

After the foregoing description of the several parts and their detail action the following explanation of the automatic operation of the whole machine will make my invention clear.

I will suppose the reels W to be supplied with paper, and the eyelet-supplying apparatus attached and furnished with a quantity of eyelets, when power is applied to the driving-pulley, which causes the lug H³ to strike against and carry along that one of the bars U² which is in the lowest position, (by being down in the depression w²,) and thus rotate all the arms H, carrying all the mechanisms for folding, feeding, and cutting off the paper; but when these parts have been carried about one-quarter of a circle around the shaft B the bar U², against which the lug H³ is pressing, has as-

cended the cam-surface w², so as to be lifted clear of said lug, which then passes on round with the disk E (which is constantly rotating) until it comes in contact with the third bar U² from that which it has just left, which third bar has by this time fallen down into the position occupied by the bar just released from lug H³, and is now carried round in like manner by said lug. So on the lug H³ during its continuous travel in a circle around shaft B, carries with it during the same one-quarter of its rotation successively the several lugs U². This, it will be seen, induces all four of the carriages on stands V (with all their attachments) to move with the disk E during one-quarter of its revolution, and remain stationary during the other three quarters of said disk's revolution, one of the arms H being locked by bolt a³ always during such state of rest. With this understanding of the motions of the disk E and carriages carrying the tag, let us take one of said carriages and follow it around and note the operations of the feeding, folding, cutting-off (and eyeleting and punching) mechanism, and we will then understand all, each of the said carriages and mechanisms performing the same motions and operations. I will take the carriage supposed to be in such position as to be opposite to the eyeleting mechanism—that is, nearest the plate D—and will suppose a tag to have been just eyeleted and to be laying in a finished condition on the table B². Now, the bolt a³ is forced out of the hole b³ in arm H, and the lug H³ strikes one of the bars U² and begins to move said bar, and consequently all the mechanism on arms H and I. The carriage (in the condition) just alluded to now moves on, and the first operation is the discharging from table B² of the finished tag, which is effected by the portion D³ of said table coming in contact with the stationary cam-finger F³, and being by said finger forced back, so as to leave an opening in the table B² equal in area to the area of the finished tag and immediately below or under it, so that the tag is left without any support and falls through. The moment the sliding portion of table B² has been forced back, as just mentioned, the former h² descends a short distance and insures the extrication or discharge of the finished tag. This former h² is caused to descend, as soon as the table B² is withdrawn from its under surface, by means of a spring around its shank f², very much after the fashion of the presser-foot of a sewing-machine. Before the table B² comes back to its normal condition the bar of rack F² begins to ride up the cam P² and effect the feeding-out of the proper length of paper to form another tag. To prevent the paper now being fed out from getting on top of the former h² (in its depressed position) or coming against the shank f², the former h² is made with its rear edge turned or bent up sufficiently far and at a proper angle to act as a guide to the end of the slip of paper and induce it to pass down and along under said former. Before the feed ceases, the table B² shoots back into

its former position, and the paper then continues to feed on top of said table. About simultaneously with this motion of the table the former h^2 is lifted, so as not to press on the paper while feeding along on the said table. This lifting of the former h^2 is effected by the upward motion of the carriage L^2 , (caused by the springs m^3), which is allowed to ascend by the inner end of the lever J^2 coming over a depressed or low portion in the upper face of cam K^2 . By the time the feeding ceases the lever J^2 has been so acted on by the upper face of cam K^2 as to cause it to force down again the carriage L^2 and induce the former h^2 to press on the piece of paper on the table B^2 , which paper is at the same moment severed from the strip of supply by the descent of the knife R^2 , which is forced down (as before mentioned) by the sliding outward (from shaft B) of the carriage H^2 . This carriage is moved out by the action of the vertical surface of cam K^2 against its rear or inner end, and is thus moved out to bring the former h^2 to a proper position to have the paper folded over it. The cam N^3 has commenced to operate upon the inner end of carriage M^2 and to force it outward. This action continues until the motion of carriage M^2 , by means of its slots m^2 , (acting on pins n^2 in slide-bars o^2), has caused the folding-blades $q^2 q^2$ to approach each other and bend or fold the corners of the paper up and over the edges of former h^2 into the shape seen at diagram No. 1. As soon as these folds are completed, the blades $q^2 q^2$ withdraw, and immediately afterward the carriage H^2 recedes toward the shaft B , carrying with it the former h^2 and the former i^2 , and the latter is now pressed down on the folded paper by the further action of cam K^2 on bar J^2 . By this time the carriage with the paper has traveled half-way round (the shaft B). As the carriage proceeds on its next quarter of rotation, the outer end of bar r^2 comes against the cam-shaped end of rim N^2 , and the former is forced in, causing the folding-blade s^2 to pass under the edge of the paper and fold it up over the former i^2 into shape seen at diagram No. 2. As soon as this fold is completed, the former i^2 recedes toward shaft B , leaving the folded tag under the folding-blade s^2 , and in this condition the folded paper is carried on until it arrives under punch a , where the carriage again stops and the paper is punched by the action of punches a and b , which have been already explained, and the material then presents the form seen at diagram No. 3. The next quarter-rotation of the carriage, with the folded and punched piece of paper, is around to the eyelet-inserting mechanism, which puts in an eyelet, thus completing the tag, as seen at No. 4. The folding-blade s^2 has a notch cut out in its folding-edge to accommodate the punches of the punching and eyeleting mechanisms, and said blade s^2 , it will

be seen, holds down the folded paper during the punching and eyeleting operations. The table B^2 is formed with a hole, through which work up and down the dies and punches, which operate on the paper to punch and eyelet it.

It will be understood that the operations and motions of each of the other four carriages, with all their mechanism, is the same as that just explained, and that they all move simultaneously, and that while some hold the paper in a position to receive no action or operation, others hold their paper in the proper positions to be having the punching and eyeleting operations performed thereon.

It will be seen that this machine is automatic in all its operations, and that so long as the eyeleting mechanism is kept supplied with eyelets and the reels with paper it will continue to make and discharge (at a given point) finished, folded, and eyeleted tags, such as seen at diagram No. 4.

It will be understood that very many changes in the details of this machine may be made without changing the mode of operation of its several combinations of mechanisms, and I do not wish to be limited in the protection afforded by a patent to constructing the machine in its details as shown; and I am aware that my machine is the first automatic machine ever constructed or devised for making folded tags.

What I therefore claim as of my invention, and desire to secure by Letters Patent, is—

1. An organized and automatic machine for making folded tags, in which the material, from which the tag is to be cut, folded, and punched, is supplied by an intermittent feed to a suitable table or sustaining surface, where it has performed upon it all the operations requisite to produce a folded tag.
2. In combination with a mechanism for folding over the end of the strip of material, a mechanism for feeding the material to the proper position to be folded.
3. A folding mechanism in combination with an eye forming or punching mechanism.
4. The employment, in combination with a folding mechanism, of a cutting-off knife or its equivalent.
5. The combination of a folding mechanism, a feeding mechanism, and a cutting-off device.
6. The combination of an eyeleting mechanism with a folding mechanism.
7. The combination of a folding mechanism, an eye-punching mechanism, and an eyeleting mechanism.

In testimony whereof I have hereunto set my hand and seal.

T. B. DE FOREST. [L. S.]

In presence of—

LINSON DE FOREST,
CHARLES H. DE FOREST.
